BIN DISPENSER FOR VARIOUS SIZED ARTICLES

Simon Heselov, 52 E. Myrtle Ave., Youngstown, Ohio

Filed May 24, 1963, Ser. No. 75,056

Term of patent 14 years

(Cl. D80—9)

I claim:

The ornamental design for a bin dispenser for various sized articles, as shown.
